PORTABLE BASEBALL CART

Ralph A. Gonzalez, 2114 Heloise Way,
Placentia, Calif. 96270

Filed July 27, 1970, Ser. No. 24,161

Term of patent 14 years

Int. Cl. D12—02

U.S. Cl. D14—3

Fig. 1

Fig. 2

Fig. 3

Fig. 4

FIG. 1 is a top plan view of a portable baseball cart showing my new design;

FIG. 2 is a front elevation view thereof;

FIG. 3 is a left side elevation view thereof; and

FIG. 4 is a perspective view thereof.

The rear and right side surfaces of the portable baseball cart, not shown, are solid and flat.

I claim:

The ornamental design for a portable baseball cart, as shown and described.
